(57) CLAIM

The ornamental design for a container for cosmetic sponge applicators, as shown and described.

DESCRIPTION

FIG. 1 is a perspective view of the interior surface of a first half of a container for cosmetic sponge applicators showing my new design;

FIG. 2 is a perspective view of the exterior surface of the first half of the container for cosmetic sponge applicators shown in FIG. 1;

FIG. 3 is a front elevation view of the container portion shown in FIG. 1;

FIG. 4 is a rear elevation view of the container portion shown in FIG. 1;

FIG. 5 is a left side elevation view of the container portion shown in FIG. 1;

FIG. 6 is a right side elevation view of the container portion shown in FIG. 1;

FIG. 7 is an enlarged top plan view of the container portion shown in FIG. 1;

FIG. 8 is a bottom plan view of FIG. 1;

FIG. 9 is a perspective view of the interior surface of a second half of the container for cosmetic sponge applicators, with exemplary sponge applicators contained therein;

FIG. 10 is a front elevation view of the container portion shown in FIG. 9;

FIG. 11 is a rear elevation view of the container portion shown in FIG. 9;

FIG. 12 is a left side elevation view of the container portion shown in FIG. 9;

FIG. 13 is a right side elevation view of the container portion shown in FIG. 9;

FIG. 14 is an enlarged top plan view of the container portion shown in FIG. 9;

FIG. 15 is a bottom plan view of FIG. 9;

FIG. 16 is a perspective view of the container for cosmetic sponge applicators, shown with the first half of the container of FIGS. 1-8 and the second half of the container shown in FIGS. 9-15 in an assembled state; and,

FIG. 17 is a perspective view showing the assembled container of FIG. 16 with a cap disposed thereon. Portions of the container for cosmetic sponge applicators were shown separately for the purpose of clarity of illustration.

The cosmetic sponge applicators and the cap shown in broken lines in the drawings form no part of the claimed design.
